UNITED STATES PATENT OFFICE

134,701

DESIGN FOR A BUILDING BLOCK

Charles A. Meade, Poughkeepsie, N. Y.

Application November 5, 1942, Serial No. 108,706

Term of patent 14 years

To all whom it may concern:

Be it known that I, Charles A. Meade, a citizen of the United States and a resident of Poughkeepsie, county of Dutchess, and State of New York, have invented a new, original, and ornamental Design for a Building Block, of which the following is a specification, reference being made to the accompanying drawing forming part thereof.

In the drawing:

Fig. 1 is a perspective view of a building block showing my new design; and

Fig. 2 is an end elevational view of same.

I claim:

The ornamental design for a building block, substantially as shown.

CHARLES A. MEADE.
